REWIND MACHINE

Leonard Rockstrom, Madison, and Robert E. Bush, Morris Plains, N.J., assignors to Cameron Machine Company, Dover, N.J., a corporation of New York
Filed Dec. 21, 1965. Ser. No. 515,336
12 Claims. (Cl. 242—65)

This invention relates to rewind machines and more particularly to novel means for controlling the quality of rewind rolls.

Rewind machines constructed in accordance with the concept of this invention are, among other possible uses, particularly useful for high speed, large capacity production where exceptionally fine roll quality is a very important consideration, such as printing paper, fine packaging paper or other special purpose papers, for example.

In one form the present invention contemplates the provision of a new and improved rewind machine comprising a battery of individual, surface-center driven, shaftless rewind stations each having an independently controlled rate of speed, torque or pull, and nip pressure for each individual rewind roll. The rewind machine is arranged to receive a relatively wide supply or mill roll of paper, plastic films, foils, thin metals, or other material to be slit, and slitting same into a plurality of subwebs, and thence, passing the subwebs partially around a main pull or contact drum, and then, alternately passing the web to front and back rewind rolls. A pair of rewind arms are provided to support each rewind roll, and individual motive means, such as a hydraulic motor is employed to drive each individual rewind roll. An individual carriage, piston and cylinder assembly is provided for each rewind roll, and accordingly, the nip pressure between the rewind roll and the contact drum is controlled individually for each particular rewind roll. Means such as potentiometers are mounted on the carriages which are operatively responsive to the position of the carriages to control the speed of the hydraulic motors, respectively. Also, means, such as a cam surface, is provided for each carriage to regulate the fluid pressure to its corresponding hydraulic motor, thereby to control the torque as the rewind roll builds-up in order to maintain a suitable draw or web pull pattern throughout the cycle. In operation the outside surface of the rewind rolls remain in engagement with the contact drum throughout the rewinding cycle, and the center of the rewind roll starts relatively close to the contact drum and during the rewinding process it moves horizontally outwardly therefrom in a carefully controlled manner by means of the carriage, piston and cylinder assembly. A front platform and a rear platform are provided, each of which carries a plurality of carriages and each pivots about its respective platform pivot point. The pivotal movement is outward so that the center of the rewind roll moves away from the center of the machine. That is, according to the invention, the individual rewind rolls move horizontally outwardly, individually, and thence collectively pivot on their platforms, from which they are discharged or released onto suitable receivers, respectively.

A feature of our invention resides in the provision of a new and improved rewind machine with which large diameter and heavy rewind rolls may be rewound and which operates at high speed compared to prior art devices.

Another feature of this invention is the provision of a new and improved machine for rewinding webs of sheet material which overcomes strain and density control problems caused by extreme conditions of elasticity, slip, moisture content and caliper variation in the web of material being rewound. A further feature of the inven-

2

tion resides in the provision of a rewind machine which does not require the use of long rewind shafts, center supports or friction core driving means.

Still another feature of our invention is the provision of means for separately controlling the surface nip pressure between the main rewind drum and each rewinding roll which is not affected by the weight of the rewind roll. Also, means are provided for individually controlling the speed and torque of the rewind roll driving means for maintaining substantially constant web speed and draw or pull.

A further feature of the invention resides in a rewind machine which provides a rapid and easy means for unloading completed rewind rolls of large diameter. Yet another feature of our invention resides in the provision of a new and improved rewind machine which is of rugged construction, which is durable in use, and which is highly efficient in operation.

Other objects, advantages and features reside in the detailed construction and operation, as more fully hereinafter described and claimed, reference being had to the accompanying drawings forming part thereof, wherein like numerals refer to like parts throughout, and in which:

FIG. 1 is a perspective view of a rewind machine constructed in accordance with the concepts of this invention;

FIG. 2 is a schematic plan view showing front and rear portions of the rewind machine;

FIG. 3 is a side elevation, partially in section, of the rewind machine of FIG. 1;

FIG. 4 is an enlarged perspective view showing details of the platforms which carry the carriages, one being provided for each pair of rewind arms; and

FIG. 5 is an enlarged perspective view showing details of the cam and potentiometer control means for controlling the rewinding operation.

In the illustrated embodiment of the invention, the rewind machine comprises a front portion designated generally at 10 and a rear portion designated generally as 12, FIGS. 1, 2 and 3. As best seen in FIG. 3, there is a relatively wide supply or mill roll 14 of paper, plastic film, foil, thin metal or other material to be slit. A web 16 is fed from the supply roll 14 over rolls 18 to a cutting roll 20 where slitters or cutters 22 cut the web into strips or subwebs of the desired rewind width as the web material passes thereby. The web then passes over a roll 24 to the main pull or contact drum 26, and then alternate webs pass to the front rewind rolls 28 and 30 and to the rear rewind rolls 32 and 34. As best seen in FIG. 2, the rewind rolls 28, 30, 32 and 34 are disposed in staggered relation one with respect to the other.

It will be appreciated that the front portion 10 and the rear portion 12 of the rewind machine are substantially identical and operate in substantially the same manner, therefore, only the front portion will be described in detail. Referring to FIG. 1, rewind roll 28 is mounted towards the top end of rewind arms 36 and 38 and rewind roll 30 is mounted towards the top end of rewind arms 40 and 42. Also, hydraulic motors 44 and 46 are mounted towards the top end of one of each pair of rewind arms 36, 38 or 40, 42 (FIG. 2), respectively. That is, an individual hydraulic motor is provided for each rewind roll, individual controls for the hydraulic motors being described more fully hereinafter.

The rewind arms 36 and 38 are carried on a carriage 48 as by means of a transversely disposed track 50. That is, the rewind arms 36 and 38 are transversely adjustable depending upon the width of the rewind roll to be rewound. Rewind arms 40 and 42 are mounted on carriage 52 in like manner. As best seen in FIG. 1, carriages 48 and 52 are each independently mounted on platform 54

by means of bedways 56, 58, 60, 62 provided for the purpose. The coefficient of friction of each carriage on its respective bedways is as low as possible for purposes of providing more accurate control of the nip force between the rewind roll and the main drum.

As best seen in FIG. 4, carriage 48 is provided with a pair of brackets 64, 68 to which piston rods 70, 72 are pivotally connected, respectively, said rods being actuated by their respective pneumatic cylinders and piston assemblies 74, 76 which are mounted on the platform 54.

As best seen in FIG. 3, during the buildup of the rewind roll 28, it moves outwardly in a horizontal plane indicated at 78. That is, the center line of the main drum 26, center line of the rewind rolls 28 and 32 and the tangent or contact points 80 and 82 between the rewind rolls and the main drum, respectively, are all in a horizontal plane. In this manner the weight of the rewind roll during buildup is negated and the nip or contact force between the rewind roll and the main drum at the point 80 can be carefully controlled by controlling the horizontal movement of each individual carriage moves horizontally on low friction bedways in a second horizontal plane motivated by the action of the pneumatic cylinder and piston assemblies 74, 76 (FIG. 4), whereby control of said pneumatic cylinder and piston assemblies controls the nip force between the rewind rolls and the main drum. Further, it is noted that each individual rewind roll is provided with its own rewind arms, carriage, and cylinder and piston assembly so that the nip force for each rewind roll is individually controlled.

Referring next to FIG. 5, there is shown a potentiometer 84 mounted on the platform 54 and operatively connected to the carriage 48 to send an electrical impulse through connector means 86 to controller 88 (FIG. 2), as will be described more fully hereinafter. As best seen in FIG. 5, a cam surface 90 is mounted on platform 54, adjusting means 92 being provided for the accurate positioning thereof. A cam follower 94 is mounted on carriage 48 to follow the cam surface and operate a relief valve 96 to transmit a signal through connector means 98 to controller 88 (FIG. 2). Thus, it is seen that horizontal in and out movement of the carriage 48 (FIG. 5) causes the transmission of predetermined signals to the controller 88 (FIG. 2) through connectors 86 and 98. As is schematically shown in FIG. 2, hydraulic fluid under pressure is received from a source 100 into the controller 88 wherein it is modulated to deliver to the hydraulic motor 44 through connector 102. The control 88 serves to control the volume of fluid transmitted to the hydraulic motor 44 in response to the signal received from the potentiometer 84 (FIG. 5) through connector 86 (FIG. 2). The volume of fluid, in turn, controls the speed at which the rewind roll 28 is driven so that the speed is decreased as the rewind roll builds up in diameter in order to maintain a substantially constant web speed. The controller 88 (FIG. 2) also serves to control the pressure of the hydraulic fluid entering the hydraulic motor 44 responsive to the movement of the cam follower 94 (FIG. 5). This, in turn, controls the winding torque of the rewind roll 28. During the buildup of the rewind roll the torque is gradually increased in order to keep a substantially constant pull or draw on the web throughout the rewinding cycle. Thus it is seen each rewind roll 28, 30, 32 and 34 is provided with its own hydraulic motor drive and each motor is controlled by its own potentiometer and cam assembly. Accordingly, rewind rolls of various widths, diameters or different physical characteristics can be handled, simultaneously.

Referring to FIG. 1, it is seen that carriages 48 and 52 are both slidably mounted on platform 54. It is noted that a rear platform is also provided which is similar to the front platform. After the rewind rolls 28 and 30 have been completed and moved to their outermost position on the platform 54, the entire platform including the carriages is pivoted about its pivot point 104, the

rewind roll 28 moving from its position shown by the solid lines to its position shown by the broken lines in FIG. 3. The pivot point 104 is a shaft which extends the entire width of the machine as seen in FIG. 4, the ends being mounted in the main frame of the machine 106. For each platform 54, there are four downwardly depending brackets 108, to each of which is pivotally connected a piston rod 110 which, in turn, is connected to a hydraulic cylinder and piston assembly 112 (FIG. 3), the cylinder being pivotally mounted on the main frame 106 as at 114.

As best seen in FIG. 3, after the rewind rolls have been completed, the hydraulic cylinder and piston assembly 112 pivots the platform 54 so that the rewind rolls move outwardly and are positioned on a transversely moving conveyor belt 116 which carries the rolls away. It will be appreciated that all the rolls may be released simultaneously onto the conveyor belt. The conveyor is located at floor level and a pit 118 (FIG. 3) is provided to receive the overhanging components during pivotal movement. Thereafter, the platform is returned to its horizontal position and the carriages are returned to their innermost positions ready to start the next cycle of operation. As pointed out hereinbefore, rewind rolls are built up and discharged onto a transverse conveyor in the rear portion 12 of the machine the same as in the above described front portion 10.

Thus, it is seen that applicants have indeed provided a new and improved rewind machine which effectively meets the objects specified hereinbefore.

In view of the foregoing description, taken in conjunction with the accompanying drawings, it is believed that a clear understanding of the construction, operation and advantages of the device will be quite apparent to those skilled in the art. A more detailed description is accordingly deemed unnecessary.

It is to be understood, however, that even though we have herein shown and described a preferred embodiment of our invention, the same is susceptible to certain changes fully comprehended by the spirit of the invention as herein described and the scope of the appended claims.

Having thus described the invention, what we claim is:

1. In a rewind machine, the combination of a front group and a rear group, each group comprising a plurality of pairs of rewind arms, and each pair arranged to support a rewind roll at their outer ends, a main contact drum disposed in operational engagement with the rewind rolls, a front platform for said front group and a rear platform for said rear group, a plurality of carriages carried by each of said platforms one being provided for each pair of rewind arms, individual means mounting each of said carriages for horizontal movement away from said main contact drum responsive to the buildup of its corresponding rewind roll, and means for pivoting each of said platforms with their corresponding carriages away from said main contact drum when the respective group of rewind rolls has been completed.

2. A rewind machine according to claim 1 wherein the rewind roll is supported at the outer ends of said rewind arms on a rewind roll core and is formed from a strip of sheet material wound about said core, and the centerline of said contact drum and the centerlines of said rewind rolls are disposed in the same horizontal plane.

3. A rewind machine according to claim 2 wherein said means mounting each of said carriages comprises low friction bed ways positioned in a horizontal plane different from the first mentioned plane, and said carriages are mounted on said bed ways respectively for horizontal movement away from said main contact drum responsive to the buildup of its corresponding rewind roll.

4. A rewind machine according to claim 3 wherein one of said arms of each pair carries at its outer end means for center driving engagement with said core, and means are provided for applying a predetermined pressure on

said carriages whereby a controlled density is obtained throughout the thickness of the rewind rolls respectively.

5. A rewind machine according to claim 2 wherein one of said arms of each pair carries at its outer end means for center driving engagement with its respective core, and wherein said main contact drum is disposed in surface to surface driving engagement with the rewind rolls, and means are provided for applying a predetermined pressure on said carriages whereby a controlled density is obtained throughout the thickness of the rewind rolls, respectively.

6. A rewind machine according to claim 2 characterized by transversely extending conveyor means disposed adjacent said pivoted platforms, respectively, for receiving said so pivoted completed rewind rolls.

7. A rewind machine according to claim 4 wherein said main contact drum is disposed in surface to surface driving engagement with the rewind rolls, said means for applying a predetermined nip pressure on said carriages comprises fluid cylinder and piston means, and said means for pivoting each of said platforms comprises fluid cylinder and piston means, and transversely extending conveyors are disposed adjacent said pivoted platforms, respectively, for receiving said so pivoted completed rewind rolls.

8. A rewind machine according to claim 5 further comprising means for controlling the speed of said means for center driving engagement with said core corresponding to the build-up of said rewind rolls, respectively.

9. A rewind machine according to claim 5 further comprising means for controlling the torque output of said means for center driving engagement with said core corresponding to the build-up of said rewind rolls to maintain a predetermined web pull, respectively.

10. A rewind machine according to claim 2 wherein one of said arms of each pair carries at its outer end a hydraulic motor for center driving engagement with its respective core, and wherein said main contact drum is disposed in surface to surface driving engagement with the rewind rolls, potentiometer means are associated with said carriages for controlling the volumetric flow of hydraulic fluid to said hydraulic motors corresponding to the relative position of said carriages respectively with respect to said main contact drum, and means are provided for applying a predetermined pressure on said carriages whereby a controlled density is obtained throughout the thickness of the rewind rolls, respectively.

11. A rewind machine according to claim 2 wherein one of said arms of each pair carries at its outer end a

hydraulic motor for center driving engagement with its respective core, and wherein said main contact drum is disposed in surface to surface driving engagement with the rewind rolls, cam means associated with said carriages for controlling the pressure of the hydraulic fluid being supplied to said hydraulic motors corresponding to the relative position of said carriages respectively with respect to said main contact drum to maintain a preselected web pull pattern throughout the cycle, and means are provided for applying a predetermined pressure on said carriages whereby a controlled density is obtained throughout the thickness of the rewind rolls, respectively.

12. A rewind machine according to claim 2 further comprising transversely extending conveyor means disposed adjacent said platforms, respectively, for receiving said so pivoted completed rewind rolls, and wherein said main contact drum is disposed in surface to surface driving engagement with the rewind rolls, means for applying a predetermined pressure on said carriages comprising fluid cylinder piston means, and said means for pivoting each of said platforms comprises fluid cylinder and piston means, and wherein one of said arms of each pair carries at its outer end a hydraulic motor for center driving engagement with its respective core, and wherein potentiometer means are associated with said carriages for controlling the volumetric flow of hydraulic fluid to said hydraulic motors corresponding to the relative position of said carriages respectively with respect to said main contact drum, and wherein cam means associated with said carriages for controlling the pressure of the hydraulic fluid being supplied to said hydraulic motors corresponding to the relative position of said carriages respectively with respect to said main contact drum to maintain a predetermined web pull pattern throughout the cycle, whereby a controlled density is obtained throughout the thickness of the rewind rolls, respectively.
